UNITED STATES PATENT OFFICE.

FREDERICK K. WRIGHT, OF SYRACUSE, NEW YORK, ASSIGNOR TO R. E. DIETZ COMPANY, OF NEW YORK, N. Y.

LANTERN.

No. 850,455.

Specification of Letters Patent.

Patented April 16, 1907.

Application filed May 20, 1904. Serial No. 208,828.

To all whom it may concern:

Be it known that I, FREDERICK K. WRIGHT, a citizen of the United States, and a resident of Syracuse, in the county of Onondaga and 5 State of New York, have invented a new and useful Improvement in Lanterns, of which the following is a specification.

This invention relates to that class of lanterns which contain a wire guard frame or 10 basket and a top or dome of sheet metal which is connected with the top ring of the frame at the rear by a hinge and at the front by a spring-catch.

Heretofore the hinge and the guide-loop 15 for the spring-catch have usually been made of sheet metal and riveted to the skirt of the lantern-top.

The object of this invention is to construct the hinge of wire in order to simplify, 20 strengthen, and cheapen the connection.

In the accompanying drawings, Figure 1 is an elevation, partly in section, of the upper portion of a lantern provided with my improvements. Fig. 2 is a bottom plan view of 25 the lantern-top. Fig. 3 is a perspective view showing the wire hinge before the same is applied to the lantern top and frame. Fig. 4 is a perspective view showing the wire hinge applied to the lantern-top and frame-ring. 30 Fig. 5 is a top plan view showing the wire hinge applied to the lantern-top and guard-frame.

Like letters of reference refer to like parts in the several figures.

35 A represents the sheet-metal top or dome of a lantern, and a the flange of said top. B represents the top ring of the wire guard-frame, and C the uprights of said frame. All 40 of these parts may be of any suitable or well-known construction.

D represents the wire hinge by which the top A is connected to the top ring B on the rear side of the lantern. This hinge is bent to form a cross-bar d and curved end portions 45 d'. The latter stand at right angles to the cross-bar and have the form of hooks which are turned with their open sides upwardly. The flange a of the top is provided near its edge with two openings e, through which the 50 two hooks d' are inserted from above, so that the cross-bar d of the hinge rests upon the

flange a between these openings and the hook portions d' of the hinge extend outwardly below the top ring B of the frame and upwardly on the outer side of the flange a, as indicated 55 by dotted lines on the left-hand side of Fig. 1. The upwardly-projecting end portions of the hooks are then closed down upon the flange a, as shown in full lines in Fig. 1, whereby the hinge is firmly attached to the lantern-top 60 and connected with the top ring of the lantern-frame, so as to turn on its curved end portions in swinging the top on the hinge. The top ring of the frame is preferably offset, as shown at f, Fig. 2, to receive the hinge and 65 prevent the latter from shifting its position circumferentially on the top ring.

G represents the usual spring-catch which is attached to the under side of the lantern-top and arranged at the front thereof for engagement with the top ring of the frame when the lantern-top is closed down. H represents the wire guide-loop which is also secured to the under side of the lantern-top and in which the free end of the catch is loosely 70 held and guided near the thumb-piece g of the catch. This guide-loop is bent to form an eye h and attaching-arms h', which extend in opposite directions from the eye.

The hinge is made of wire and easily bent 80 to shape and attached by suitable tools, whereby the cost of production is greatly reduced, and the connection of the lantern-top with the guard-frame is rendered strong and durable.

85 I claim as my invention—

The combination of a lantern-top, a lantern-frame, and a connecting wire hinge consisting of a cross-piece which rests upon the top and end portions which extend downwardly through openings in the top, then outwardly underneath the top ring of the lantern-frame, and then upwardly and inwardly over the marginal portion of the top against which they are closed down, substantially as 90 set forth.

Witness my hand this 14th day of May, 1904.

FREDERICK K. WRIGHT.
